UNITED STATES PATENT OFFICE.

ALFRED H. PEIFFER, OF PHILADELPHIA, PENNSYLVANIA, ASSIGNOR TO THE SIMONS BROTHER & COMPANY, OF SAME PLACE.

DESIGN FOR A SOUVENIR SPOON.

SPECIFICATION forming part of Design No. 21,409, dated March 15, 1892.

Application filed February 1, 1892. Serial No. 419,997. Term of patent 7 years.

To all whom it may concern:

Be it known that I, ALFRED H. PEIFFER, a citizen of the United States, residing at Philadelphia, in the county of Philadelphia and 5 State of Pennsylvania, have invented and produced a new and useful Design for Spoons and Similar Articles, of which the following is a specification, reference being had to the accompanying photograph.

10 My design does not have reference to the particular shape of the spoon itself, but refers more particularly to the decoration or ornamentation thereof, and is intended for a souvenir spoon appropriate to the city of Philadelphia. The handle of the spoon is more or 15 less decorated about its edge with a scroll pattern, as shown. On the surfaces included within this scroll pattern are representations of buildings or views appropriate to the city 20 of Philadelphia. On the upper portion of the handle is a representation of the public build-

ings of that city. Below this is a representation of the old State House of Philadelphia, to which may be added the date of "1776." Below this upon the handle is a representation of 25 the pipe of peace and a quill pen, together with a scroll indicative of the Penn treaty. Upon the bowl of the spoon is a design representing American Indians viewing the landing of Columbus.

Having now described my design, what I claim as new, and desire to secure by Letters Patent, is—

The design for a souvenir spoon, substantially as described and shown.

In testimony of which invention I have hereunto set my hand.

ALFRED H. PEIFFER.
